(57) **CLAIM**

The ornamental design for a one hand computer keyboard, as shown and described.

DESCRIPTION

FIG. 1 is a perspective view of a one hand computer keyboard showing my new design;

FIG. 2 is a top plan view thereof;

FIG. 3 is a cross-sectional view taken along line 3—3 of FIG. 2;

FIG. 4 is a cross-sectional view taken along line 4—4 of FIG. 2.

FIG. 5 is a cross-sectional view taken along line 5—5 of FIG. 2.

FIG. 6 is a cross-sectional view taken along line 6—6 of FIG. 2.

FIG. 7 is a side elevational view of the keyboard shown in FIG. 1, taken to a side view as indicated by arrow 7 in FIG. 1.

FIG. 1 showing the side opposite that shown in FIG. 1; FIG. 8 is an end view of the keyboard shown in FIG. 1

showing the end opposite that shown in FIG. 1; and, FIG. 9 is a bottom plan view thereof.

The broken lines are for illustrative purposes only and form no part of the claimed design and FIGS. 7-9 are shown on

a greatly reduced scale.
